UNITED STATES PATENT OFFICE.

HORACE L. KENT, OF NEW YORK, N. Y.

MILL.

Application filed August 12, 1921. Serial No. 491,687.

To all whom it may concern:

Be it known that I, HORACE L. KENT, a citizen of the United States of America, residing at New York city, county of Kings, 5 New York, have invented a new and useful Mill, of which the following is a specification.

My invention relates particularly to mills for crushing stone and other materials. The 10 main object is to increase the efficiency and capacity of the mill.

The invention is more particularly directed to mills of that type having a rotating ring and a series of crushing rolls.

15 The details of the improvement will be understood from the following specification and claims.

Figure 1 is a vertical projection and partial section of a mill embodying one form 20 of the improvements of my invention;

Fig. 2 is an end view and partial section of the same;

Fig. 3 is a fragmentary sectional view;

25 Fig. 4 is a vertical sectional view of a modification; and

Fig. 5 is a fragmentary sectional view of a modification.

In the form shown in Figs. 1, 2 and 3 the ring 10 is freely rotatable and has a 30 groove which receives one or more crushing rolls. In the case herein shown there are four rolls 11, 12, 13 and 14. The shape of the rolls and the groove in the ring co-operate to crush the material between them.

35 Each of the rolls is mounted on a shaft extending transversely through the ring, such as the shafts 15 and 16. Each shaft is supported in a bearing carried by a member, such as 17, which is adapted to slide radially in a sleeve 18. Each of the shafts is

40 pressed outwardly by means of a spring, such as 19, so that all of the crushing rollers are yieldingly pressed into the groove or track in the ring. One of the shafts 45 may be driven by suitable means so that its rollers will frictionally drive the ring, and the ring in turn will drive the other rollers.

The ring and rollers are enclosed in a suitable housing 20, which is 50 provided at one or more sides with a hopper or chute 21, through which the material to be crushed is fed. The bottom of the chute is subjected to the abrasive action of the material being ground, and with some materials the bottom wears

very rapidly. I have provided a removable bottom section 21', which may be removed when worn and replaced by a new section. The lower end of the bottom section preferably has a downwardly-extending portion 60 which is substantially flush with the inside of the housing, and the wear will be taken by the bottom and not by the housing. To facilitate the delivery of material to the groove or track in the ring 10 between the 65 rollers, I preferably provide an inclined flange 22, which extends up close to the edges of the rollers. I also provide the ring 10 with flanges 23, which extend laterally beyond the edges of the rollers and inwardly 70 toward the axis of the ring. These flanges 23 serve not only to increase the initial capacity of the ring, but they serve to retain the material in the ring for a much longer time than is possible with a ring whose 75 width is no greater than the width of the roller. Material which passes between the rollers and the ring is crushed or broken and, due to centrifugal force, tends to fly outwardly. The mass being ground will 80 consist of coarse and fine particles. The larger particles during the rotation will work to the bottom of the ring and be crushed between the ring and rolls, while the finer particles in the mass will work upwardly or toward the edge of the ring and, during the operation of the mill, will be forced along the flanges 23 and over the edge thereof. The flanges 23 serve to retain the material until the proper degree 85 of fineness is attained. In the form shown a substantially annular space is provided at each side of the ring for the discharge of the crushed material.

90 It will be noted in Figs. 1 and 3 that the flanges 22 and 23 overlap, that is, the flange 22 extends inside of the flange 23 of the ring. It is therefore practically impossible for material which is being fed into the mill through the chute 21 to fall through without being acted upon by the crushing rollers.

95 In the present instance four rollers are shown in a ring, and each of two rollers are mounted diametrically opposite each other. The strains are thus more nearly equalized than if, say, three equidistantly spaced rollers were provided. With the form shown, when a large piece of material gets between the ring and one roller, the spring on the 100 opposite roller is stressed, while, if three 110

rollers were provided, the springs on the two rollers opposite would be stressed and parts of the mill might be broken.

Although the apparatus thus far described embodies improvements in the art which may be used by themselves, I have illustrated those improvements in connection with what may be termed a duplex unit, which has advantages of its own. In the duplex unit construction I provide each shaft with two sets of rollers, one set of which co-acts with the ring 10, and the other set of which co-acts with the ring 10'. The bearings for each shaft are preferably carried by a cross-piece or yoke 24, which has a central recess for the spring 19, so that a single spring serves to equalize the pressure on the bearings at the opposite ends of the shaft. These two sets of rollers and rings are located close together, but preferably spaced apart by a partition 25. The partition is preferably provided with flanges 22, corresponding to the flanges on the outer housing. This arrangement provides four substantially annular discharge openings from the rings into the housing, instead of two, as in the single ring construction. The partition also strengthens the mill and enables the two sets of rollers and rings to operate more or less independently of each other. By mounting two rollers on each shaft, the crushing strains are more evenly distributed as each roller is somewhat controlled by the action of the other roller, and neither roll can search out individual soft spots in its ring and hammer flat surfaces in the ring, as sometimes occurs in single unit constructions.

By using four rollers with each ring, it is possible to locate the inlet chute between two rollers with an obtuse angle, thereby reducing the tendency of the fed-in material to flow over the sides of the ring. With a steep inlet angle there is less wear on the walls of the chute.

In Fig. 4 I have illustrated certain features of the invention as applied to a modified form of construction. In this case the ring 30 is carried by a web 31 secured to the shaft 32, which is driven by suitable means. The rollers 33 engage within the ring and are adapted to be driven thereby. The housing and ring are provided with overlapping flanges 34 and 35 in a manner similar to that previously described. The web or partition 31 is likewise preferably provided with flanges corresponding to the flanges 34. I have also illustrated this construction as applied to a duplex mill with a second ring 30' and corresponding co-operating rollers. In this case the web 31 serves as a partition between the two rings.

In Fig. 5 is illustrated a modified form of ring and roller. The ring in this form is provided with side flanges 36, the edges of

which are turned inwardly toward the transverse plane of the roller, as at 37. The in-turned edges serve to retain the material in the ring better than a plain flange. In order to provide ample free space for the passage of material to a point between the ring and roller, the latter may be recessed, if desired, as at 38.

I claim:

1. In a crushing mill, a grooved ring, a plurality of rollers engaging within said ring, a housing enclosing said ring and rollers, said ring having continuous flanges extending therearound at opposite sides; and said housing having substantially continuous annular flanges, the flanges on said housing overlapping and extending within and being spaced from the flanges on said ring whereby material fed into the housing is prevented from falling outside of the ring, there being formed a narrow annular space for discharge of crushed material over the outer edges of the flanges on the ring between the spaced apart annular flanges on the housing and ring. 90

2. In a crushing mill, a housing, a plurality of crushing rollers, an annular ring surrounding said rollers and cooperating therewith to crush material, said ring being of greater width than said rollers, and a substantially continuous annular flange on said housing projecting inwardly beyond and overlapping the edge of said ring and in close proximity thereto whereby material fed into said ring will be prevented from falling outside the ring, there being a narrow annular space for discharge of crushed material over the edge of the ring between the annular flange on the housing and the edge of said ring. 100

3. In a crushing mill, a housing, a plurality of rollers, a grooved ring surrounding said rollers and adapted to cooperate therewith for grinding material, said ring being of greater width than said rollers, and an annular flange carried by said housing at each side of said ring and projecting inwardly beyond the edges thereof to a point slightly removed therefrom whereby material fed into said ring will be prevented from falling outside the ring, there being an annular space for discharge of crushed material over the edges of the ring between the annular flanges and the edges of the ring. 110

4. In a crushing mill, a plurality of sets of crushing rollers, a corresponding plurality of rings surrounding said rollers and adapted to co-operate therewith for crushing material, an annular partition between said rings and flanges projecting from said partition for deflecting material fed into said rings away from the edges thereof and between the rings and crushing rollers. 125

5. In a crushing mill, a plurality of sets of crushing rollers, a corresponding plural-

ity of rings surrounding said rollers and adapted to co-operate therewith for crushing material, a housing for said rings and rollers, a partition between said rings, said partition and said housing having flanges thereon projecting inwardly toward said rings for deflecting material fed into the rings to points between the rings and crushing rollers.

5

10 6. In a crushing mill, a plurality of crush-

ing rollers, a ring surrounding said rollers and co-operating therewith for crushing material, said ring having a continuous flange thereon with its free edge directed inwardly toward the transverse plane of said rollers, and means for rotating said plurality of rollers and ring relatively to each other.

15

HORACE L. KENT.
